UNITED STATES PATENT OFFICE.

CHARLES F. MARKHAM, OF PROVIDENCE, RHODE ISLAND.

PIN.

1,073,769.

Specification of Letters Patent. Patented Sept. 23, 1913.

Application filed March 10, 1913. Serial No. 753,162.

To all whom it may concern:

Be it known that I, CHARLES F. MARKHAM, a citizen of the United States, and resident of the city of Providence, in the 5 county of Providence and State of Rhode Island, have invented certain new and useful Improvements in Pins, of which the following is a specification.

This invention relates to certain new and 10 useful improvements in pin-stems for brooches, buckles, cuff-pins, or the like.

The object of this invention is to provide a pin-stem that may be constructed of wire, the same being pointed at one end and provided with a head at the opposite end to receive the pivot pin, said head being constructed by bending the wire around in a loop form providing an eye for the pivot and forming an extension of a portion of 15 the stock on the under side of the head, the same projecting rearwardly of the pivot point to provide a fulcrum surface adapted to engage the rear wall of the pin body before the point of the pin engages the catch.

20 In the application of the pin-stem to such articles as brooches or the like, it is found necessary to provide a fulcrum point against which the pin must rest to effect a spring tension for the point when pressed into the 25 catch or keeper.

The ordinary form of pin-stem is provided with a head having a fulcrum point on its front edge beneath the stem and where no back plate is used on the pin body, and 30 the joint ears are made integral therewith, it has been necessary in using the usual style of pin-stem to form an extremely shallow pin body in order to provide a resting place, fulcrum or support for the pin on the bottom of the body, thus limiting or controlling 35 to some extent the shape or style of the pin body. In some cases the body has been built up on the inside or a support formed therein to provide the necessary rest or ful-

40 crum point.

The above difficulty is entirely obviated by the use of my improved construction which provides a pin-stem whose head is formed with a fulcrum surface on the side 45 of the stem opposite to that from which the stem itself projects, so that the head may bring up against the rear wall of the pin body or at some point in the rear of the pivoting point, by which arrangement the construction of the pin body is greatly simplified, the expense is reduced, and the depth,

shape or style of the pin body is not limited or controlled in any way by the action of the pin-stem pivoted therein, the only limitation being the position of the joint ears 60 relative to the end wall of the pin body.

With these and other objects in view, the invention consists of certain novel features of construction, as will be more fully described and particularly pointed out in the 65 appended claim.

Of the accompanying drawings: Figure 1— is an enlarged view showing the stock from which my improved pin-stem is formed, said stock being in the form of a 70 piece of wire. Fig. 2— illustrates the second step which is that of pointing one end and bending the other around in a loop to form an eye for the pivot. Fig. 3— is a perspective view showing the head portion in 75 the finished form which is preferably obtained by flattening and swaging the head illustrated in Fig. 2. Fig. 4— shows a modification in which the rearwardly extending portion is provided by bending the 80 wire into a rearwardly and downwardly extending leg, instead of swaging the wire as shown in Fig. 3. Fig. 5— is a top view showing the head portion flattened. Fig. 6— illustrates my improved pin-stem as applied to a pin body showing the rear wall of 85 the pin body as providing a fulcrum for the pin-stem. Fig. 7— is the same as Fig. 6 showing the rear wall of the pin body as also providing a back stop for the pin-stem. 90 Fig. 8— is an enlarged transverse section on line 8—8 of Fig. 6 showing one construction of pin body in which my improved pin-stem may be mounted. Fig. 9— is a blank 95 from which a pin body adapted to receive my improved pin-stem may be struck.

Referring to the drawing, 10 designates the body of the pin-stem which is preferably constructed of round wire, but wire of other shapes in cross section may be used if desired. One end of this wire is pointed as at 11 and the opposite end 12 is bent around into a loop, as illustrated in Fig. 2, forming an eye 13 through which the pivot or pintle may pass. A pin-stem constructed in this 100 shape simply bent around to form an eye for the pintle when mounted in a pin body requires a fulcrum of some sort to be formed upon the pin body and engage the pin-stem forward of the eye, and in order to avoid 105 the expense of providing such a fulcrum, which in a so-called "one piece" pin is 110

- difficult and expensive to obtain, I go further in the construction of the pin-stem, and flatten by swaging or otherwise, the looped shape head on both sides as at 14—14, see 5 Fig. 5, and at the same time draw out and shape a rearwardly projecting portion 15, see Fig. 3, which portion is provided with an outer engaging fulcrum surface 16 on its rearwardly extending portion.
- 10 Another way of providing this rearwardly extending portion on the pin-stem head is by bending the stock part way around the eye portion 13, then downwardly and rearwardly, as at 17, and then doubling the stock 15 back upon itself as at 18 and carrying the end 12 around to practically abut the underside of the stem. In this way the rearwardly extending fulcrum engaging portion is formed in the head by bending the stock 20 instead of swaging. The sides of the head after having been constructed as illustrated in Fig. 4 may be slightly flattened if desired, to make the head thinner.
- The pin body in which my improved pin-stem is designed to be mounted is provided 25 with a rear transverse wall or abutment 19, see Figs. 6 and 7, which may extend up nearly as high as the joint ears 20, if desired, whereby the rearwardly extending portion 30 15 of the pin-stem will engage the inner face of this rear wall before the point of the pin is engaged with the catch for the purpose of providing sufficient spring in the pin-stem to cause the pointed end, when engaging the 35 catch, to be retained firmly therein. It will be noted that the abutment 13 is substantially perpendicular to the plane of the body 1 and at the rear end of said body. By the "rear end" I wish to be understood as referring to the end farthest from the end to which the catch member is applied. Another feature of this upwardly extending transverse wall in the pin body is that its upper edge may serve as a back stop for the 40 pin-stem as illustrated in Fig. 7, to limit the rearward swing of the pin-stem while being passed through the fabric to which the pin is to be attached. In practice millions of 45 these little pin-stems are made and used 50 every year, and any reduction in the cost of

construction, even though slight, means much to the manufacturer.

Other advantages in the construction and practical operation of my improved pin-stem are:

First, it may be made of round wire, the body of which being already smooth needs no further finishing, one end of this wire needs only to be pointed and the other end looped into my improved form to provide 60 the fulcrum surface and the eye for the pintle, which operations may be performed automatically, the wire being fed to one end of the pin-stem forming machine and the finished product dropped out complete at its 65 opposite end, thereby reducing the cost of construction to the very minimum.

Second, by constructing my pin-stem of round wire bent in the shape described there is absolutely no waste or scrap to the stock 70 whatever. On the contrary when made of flat stock there is considerable waste.

Third, the number of operations of forming the pin of round wire is materially reduced.

Fourth, by the use of my improved pin-stem the construction of the pin body itself is simplified, as the rear wall of the body naturally provides a fulcrum wall for the stem without the employment of other means 80 in the pin body for accomplishing this purpose.

I claim:

A pin comprising a body formed of sheet metal having ears bent to form a pin tongue 85 joint and an abutment wall substantially perpendicular to the plane of said body, and a wire pin tongue having one end bent into a loop pivotally mounted between said ears, a portion of the wall of said loop being extended rearwardly to form a fulcrum surface arranged to bear against said abutment when the pin is closed, said abutment being located adjacent the rear end of said body.

In testimony whereof I affix my signature 95 in presence of two witnesses.

CHARLES F. MARKHAM.
